CLAIM

The ornamental design for a wire harness connector, as shown and described.

DESCRIPTION

FIG. 1 is a front, top and left side perspective view of a wire harness connector, which consists of a clip and a body, in a connected state, showing our new design;

FIG. 2 is back, top and left side perspective view thereof; FIG. 3 is a front, top and left side perspective thereof, in a disconnected state;

FIG. 4 is a left side elevation view thereof, in a connected state;

FIG. 5 is a right side elevation view thereof;

FIG. 6 is a top plan view thereof;

FIG. 7 is a bottom plan view thereof;

FIG. 8 is a front elevation view thereof;

FIG. 9 is a back elevation view thereof;

FIG. 10 is a back, top and left side perspective view of the clip of a wire harness connector thereof;

FIG. 11 is a front, top and left side perspective view thereof;

FIG. 12 is a top plan view thereof;

FIG. 13 is a bottom plan view thereof;

FIG. 14 is a back elevation view thereof;

FIG. 15 is a left side elevation view thereof; and,

FIG. 16 is a right side elevation view thereof.

In the drawing, the broken line represents unclaimed environment only and forms no part of the claimed design.
